UNITED STATES PATENT OFFICE.

BENJAMIN WOLHAUPTER, OF NEW ROCHELLE, NEW YORK, ASSIGNEE TO THE RAIL JOINT COMPANY, OF NEW YORK, N. Y., A CORPORATION OF NEW YORK.

LATTICE RAIL JOINT.

Application filed September 16, 1922. Serial No. 588,612.

To all whom it may concern:

Be it known that I, BENJAMIN WOLHAUPTER, citizen of the United States, residing at New Rochelle, in the county of 5 Westchester and State of New York, have invented certain new and useful Improvements in Lattice Rail Joints, of which the following is a specification.

This invention relates to an improvement 10 in rail joint bars having for its chief object the production of a bar for that purpose involving an economical use of metal, while at the same time possessing flexibility and strength so as to be capable of carrying the 15 loads and strains as well as permitting the rail wave motion to easily pass through the joint.

To that end the invention contemplates a 20 rail joint bar utilizing a principle of girder construction which lends itself to the making of a light rail joint bar with a comparatively thin web and yet so stiffened as to easily carry the loads which are placed thereon. At the same time a substantial 25 amount of metal is saved thus materially reducing the cost of the bar to the user.

Therefore, the invention embodies in a 30 rail joint bar the desirable I-girder construction permitting the use of a relatively thin web member, and head and foot members of substantially T formation. While thus obtaining all the desirable features of a light 35 I-section in a joint bar, the present invention also proposes to stiffen and reinforce the same by stiffeners or truss members arranged within the channels at the outer and inner sides of the bar and united preferably by welding to the inner and outer flanges of both the head and foot of the bar, the said 40 stiffeners or truss members being arranged in a novel manner to readily carry the compressive and tension strains, thus giving strength and stability to the bar.

With the above and other objects in view 45 which will more readily appear as the nature of the invention is better understood, the same consists in the novel construction, combination and arrangement of parts, herein-after more fully described, illustrated and 50 claimed.

A preferred and practical embodiment of

the invention is illustrated in the accompanying drawings, in which:

Figure 1 is a vertical sectional view of a rail joint bar embodying the present improvement. 55

Figure 2 is a side elevation of the novel joint bar construction shown in Figure 1.

Figure 3 is a view similar to Figure 1 showing a modification of the invention. 60

Figure 4 is an inside view of the joint bar shown in Figure 3.

Similar reference characters designate corresponding parts throughout the several figures of the drawings. 65

In carrying the invention into effect it is proposed to provide a joint bar of substantially I-section having a vertical web portion A of minimum thickness connecting the head and foot portions B and C of the bar; the said web A being in fact so thin and light as to be incapable of carrying the loads or strains usually imposed upon the joint without the aid of proper reinforcement, such for example as proposed by the 70 present invention. Thus, according to the present invention, the web of the rail is rolled as thin as possible and yet provides an adequate connection between the top and bottom chords of the bar, thereby saving a 75 considerable amount of metal, and then the web is reinforced in a manner requiring less metal but giving adequate strength for all loading strains.

The loading strains imposed on a joint bar 80 of I-beam or girder cross-section manifest themselves in compressive strains which travel in both directions downwardly from the point where the wheel load is imposed on the head B to the several points on the foot 90 C where the latter is supported on the ties, and, as the wheel load advances along the head, this condition still holds true. It will thus be apparent that the direction of compressive strains from one point on the head 95 of the bar down to the supports for the base thereof are different from the direction of strains from another point on the head of the bar down to the same supports. This also holds true for the tensile strains. 100

Therefore, to take care of the compressive strains as well as the tensile strains, it is pro-

posed to connect the head and foot of the bar with the novel truss or reinforcing members E and E', the former providing for the strains which run from the head to the foot 5 in one direction, and the latter taking care of the strains in the opposite direction. The said truss members E and E' which are respectively arranged at the outer and inner sides of the bar, are diagonally disposed in 10 opposite directions, and, are connected to the head B and foot C of the bar, as well as the web A, along the inside edges by a suitable weld F, thereby providing in effect a lattice girder construction connecting the 15 top and bottom chords, B and C of the bar, so as to properly distribute and carry the loading strains from the head to the foot without danger of buckling or otherwise impairing the strength of the relatively thin 20 web A.

In the form of the invention shown in Figures 1 and 2 of the drawings it will be apparent that the relatively thin web A of the bar is placed in the central part or 25 axis of the head, thereby providing adequate space between the head and foot of the bar at both the inner and outer sides of the web to accommodate the oppositely inclined diagonal truss members E and E' which are arranged in crossing relation at opposite sides 30 of the web.

By this construction a splice bar of extremely light weight is formed, yet at the same time the stiffeners or truss members 35 adequately take care of all the strains travelling in either direction from the head to the foot of the bar, or vice versa, and not only prevent buckling of the web but distribute any and all loads from the head to the base 40 in a thoroughly practical and efficient manner. Also, when the stiffeners or truss members are applied to the joint members, it will of course be understood that they are spaced in such a manner as not to interfere with 45 the positioning of the bolts which are used for connecting the opposite bars of the joint.

In Figures 3 and 4 of the drawings a modification of the invention is illustrated wherein the thin web A' occupies a relatively outwardly advanced location with respect to the axis of the head B' of the bar. In this embodiment of the invention the diagonal stiffeners or truss members E² may be arranged solely in the channel at the 55 inner side of the bar, which would doubtless be sufficient for joint bars used in connection with light rails and light traffic conditions. The stiffeners or truss members E² are, of course, welded at their opposite 60 ends, as indicated at F', to the head and foot of the bar and also to the web A', thereby becoming in effect an integral part of the joint bar structure and contributing materially to the strength thereof.

65 From the foregoing it will be apparent

that the novel and distinctive feature of the present invention is the provision of a relatively light but strong joint bar which may be readily adapted to larger and higher rails which are now generally used to meet 70 the requirements of heavier rolling stock. Furthermore, an important economical advantage is gained by the material saving in metal effected by utilizing the relatively thin web portion in connection with the 75 spaced diagonal stiffeners or truss members, because the amount of metal required in the truss members is relatively small as compared with the larger amount of metal saved in thinning out the web. 80

Without further description it is thought that the features and advantages of the invention will be readily apparent to those skilled in the art and it will of course be understood that changes in the form, proportion and minor details of construction may be resorted to without departing from the spirit of the invention or scope of the appended claims. 85

I claim:—

1. A rail joint bar of I-section having inclined truss members in the channel between the head and foot portions of the bar. 90

2. A rail joint bar having stiffening members arranged in lattice truss formation. 95

3. A rail joint bar having inclined truss members in the web thereof.

4. A rail joint bar of I-section having truss members welded to the web of the bar. 100

5. A rail joint bar of I-section having truss members welded to the head, foot and web portions of the bar.

6. A rail joint bar of I-section having inclined truss members secured in the channel thereof. 105

7. A rail joint bar of I-section having inclined truss members arranged in the channel of the bar and connecting with the head and foot portions thereof. 110

8. A rail joint bar of I-section having stiffening members arranged to provide a lattice truss for the bar.

9. A rail joint bar having the head and foot portions thereof connected by a relatively thin web, and a lattice truss construction connecting the head and foot of the bar at opposite sides of the web. 115

10. A rail joint bar having the head and foot portions thereof connected by a relatively thin web, and diagonal truss members arranged in the channel formed by the head, web and foot and welded thereto. 120

11. A rail joint bar having the top and bottom chords thereof connected by a relatively thin web and inclined truss members welded to the head and foot of the bar and also to the web thereof. 125

12. A rail joint bar having the head and foot portions thereof connected by a rela- 130

tively thin web arranged in the plane of the axis of the head and forming relatively deep channels at opposite sides of the web, and diagonal truss members arranged in the 5 channels at the opposite sides of the bar and welded to the head, web and foot of the bar, the said diagonal stiffener members at one side of the bar being arranged in reverse

relation to those on the opposite side of the bar.

In testimony whereof I hereunto affix my signature in the presence of two witnesses.

BENJAMIN WOLHAUPTER.
